UNITED STATES PATENT OFFICE.

HERMAN KERNGOOD, OF BALTIMORE, MARYLAND, ASSIGNOR TO THE PERFECT CLASP COMPANY OF BALTIMORE CITY, OF MARYLAND.

DESIGN FOR A HASP FOR GARMENT-FASTENERS.

SPECIFICATION forming part of Design No. 23,255, dated May 8, 1894.

Application filed April 11, 1894. Serial No. 507,179. Term of patent 7 years.

To all whom it may concern:

Be it known that I, HERMAN KERNGOOD, a citizen of the United States, residing at the city of Baltimore, in the State of Maryland, have 5 invented a new and original Design for Hasps for Garment-Fasteners; and I do hereby declare the following to be a full, clear, and exact description of the invention, such as will enable others skilled in the art to which it applies to make and use the same.

In the accompanying drawing which forms part of this specification the hasp is shown in perspective.

The following are the leading features of 15 the design, the hasp comprises a bar α having

side swells b b , inclined parts c c at each end of the bar and lugs or ears d d in a horizontal plane below the plane of the bar α . The lugs or ears are circular and in each lug are intersected bars e e with openings or spaces f 20 between the bars.

What I claim is—

The design for a hasp for a garment fastener, substantially as herein shown.

In testimony whereof I affix my signature in 25 presence of two witnesses.

HERMAN KERNGOOD.
